UNITED STATES PATENT OFFICE.

WILLIAM A. FISHER AND ROMOLO AMICARELLI, OF LOWELLVILLE, OHIO.

BOTTLE.

Application filed January 27, 1923. Serial No. 615,405.

This invention relates to bottle constructions, and aims to provide a novel form of bottle especially designed for containing effervescing or charged liquids.

5 The primary object of the invention is to provide a bottle wherein the stopper will be held to its seat by the pressure of the liquid contained in the bottle.

10 A further object of the invention is to provide means for holding the stopper from its seat while the liquid is being poured therefrom.

15 With the foregoing and other objects in view which will appear as the description proceeds the invention resides in the combination and arrangement of parts and in the details of construction hereinafter described and claimed it being understood that changes in the precise embodiment of the invention 20 herein disclosed may be made within the scope of what is claimed, without departing from the spirit of the invention.

Referring to the drawing:—

25 Figure 1 is a side elevational view of a bottle constructed in accordance with the invention.

Figure 2 is a vertical sectional view through the upper portion of the body.

30 Figure 3 is a transverse sectional view through the neck of the bottle.

Figure 4 is a sectional view taken on line 4—4 of Figure 1.

Referring to the drawing in detail, the reference character 5 designates the body portion of the bottle, and the reference character 6 designates the neck portion thereof, the bottle being however constructed of glass or other suitable material.

40 Depressions 7 are formed in the body portion of the bottle at a point adjacent to the base of the neck, which depressions provide a pair of ribs 8 adapted to restrict the base of the neck of the bottle and provide a support for the ball valve indicated at 9 when the bottle has been emptied of its contents.

45 As shown, the neck of the bottle is enlarged at its base as at 10 and formed with curved walls 11 conforming to the curvature of the ball valve 9 to support the ball valve and guide the same to a position between the lugs 12 formed within the neck. These lugs

are formed during the moulding of the bottle proper and are arranged in spaced relation with each other presenting shoulders to be engaged by the ball valve to hold the ball valve and prevent the same from being forced into engagement with the valve seat 13, which is in the form of a washer positioned at the mouth of the bottle neck.

55 From the foregoing it will be seen that 60 when a bottle of this type has been filled with effervescing or charged liquids, the gas pressure within the bottle will act to force the ball valve 9 to its seat or to a position as indicated by Figure 2 of the drawing. 65

If it is desired to remove the contents of the bottle, it is only necessary to insert a rod or stick in the mouth of the bottle and force the valve 9 to a position behind the lugs 12 whereupon the ball is held out of 70 engagement with the valve seat and the liquid may be poured therefrom.

The ball valve 9 may now be moved from its position behind the lugs 12 by tilting the bottle neck, whereupon the gas pressure 75 within the body will again force the ball valve 9 to its seat to close the bottle.

What is claimed is:—

In a bottle construction, a body portion including a neck and mouth, depressions 80 formed exteriorly of the body portion at a point adjacent to the base of the neck to provide a pair of internal ribs, said neck having depressions formed exteriorly thereof defining a pair of internal lugs substantially 85 triangular in cross section, said lugs being substantially wide adjacent to the base of the neck and tapered to a fine point towards the mouth of the bottle, said bottle neck being curved from points adjacent to the 90 pair of ribs, to points on a line with the bases of the lugs defining pockets, and a ball valve adapted to be held between the lugs to permit pouring of material from the bottle, and said ball valve adapted to be guided 95 to its position between the lugs by the curvature of the bottle neck.

In testimony that we claim the foregoing as our own, we have hereto affixed our signatures.

WILLIAM A. FISHER.
ROMOLO AMICARELLI.
